UNITED STATES PATENT OFFICE.

WILLIAM H. McGREW, OF PERU, INDIANA, ASSIGNOR OF ONE-HALF TO
JOHN MYERS, OF SAME PLACE.

MACHINE FOR BUILDING FENCES.

SPECIFICATION forming part of Letters Patent No. 341,031, dated May 4, 1886.

Application filed February 20, 1886. Serial No. 192,686. (No model.)

To all whom it may concern:

Be it known that I, WILLIAM H. McGREW, a citizen of the United States, residing at Peru, in the county of Miami and State of Indiana, have invented a new and useful Improvement 5 in Machines for Building Fences, of which the following is a specification, reference being had to the accompanying drawings.

My invention relates to an improvement in 10 machines for building fences; and it consists in the peculiar construction and combination of parts, that will be more fully set forth hereinafter, and particularly pointed out in the claims.

15 In the drawings, Figure 1 is a side elevation of a machine embodying my invention when in use for building fences. Fig. 2 is a top plan view of the same. Fig. 3 is an elevation at right angles to Fig. 1, the wires of the fence 20 being intersected. Fig. 4 is a vertical transverse sectional view taken on the line *x x* of Fig. 2. Fig. 5 is a detail view.

The fences which my invention is adapted 25 to construct are known in the West as "wood and wire fences," and are composed of twisted strands of horizontal wires *a*, having pickets *b* interwoven in them. To construct such a fence the post *c* is driven into the ground, and the double strands of wires *a* secured thereto by means 30 of staples or in any other suitable manner.

35 The free ends of the wires are wound on spools *A*, which are journaled in arms *B*, that are carried by a vertical standard, *C*. This standard is secured on a horizontal supporting-base, *D*. A flange, *E*, projects from one side of the standard *C* at right angles thereto, and through this flange is made a series of openings, *e*, through which pass the inner ends of the arms 40 *B*. Clamping-bars *F* pass through the upper ends of the said openings and bear on the upper sides of the arms *B*, and wedges *G* pass through the lower ends of the openings and bear under the arms *B*. By tightening these wedges the bars *F* may be caused to bear 45 against the upper sides of the arms with any desired degree of force, and thus secure any requisite tension on the wires *a*, which pass from the spools *A*, between the said bars *F* and the upper sides of the arms *B*. A bail, *H*, is provided for the standard, and is attached 50 to a post, *f*, (which is driven in the ground at

one end of the fence-line,) by means of blocks and tackle *g*, or any other suitable device for moving the standard toward the said post *f*.

I represents a vertical frame, which corresponds in length to the standard *C*, and in which is journaled a series of horizontal twist-ers, *K*, which are each provided with a longitudinal central opening that extends through one end and communicates at its other end with a pair of openings, *k*, through which the wires *a* pass. These openings *k* are arranged at a suitable distance apart to admit one of the pickets of the fence to be readily inserted between the wires when the latter are held in a horizontal position, as shown in Figs. 1 and 2. The twist-ers are provided with sprocket-wheels *L*, and the frame *I* has a right-angled arm, *M*, projecting from one side, in which arm is journaled a sprocket-wheel, *N*, having a crank-shaft, *O*.

P represents an endless sprocket-chain, which connects the series of sprocket-wheels, as shown in Fig. 3, so that when the crank-shaft *O* is rotated rotary motion is imparted 75 to the series of twist-ers.

On the front side of the frame *I* are secured two guides, *R*, which are parallel flanges projecting at a right angle from the frame *I*, and are at a suitable distance apart to receive one 80 of the pickets of the fence, which is inserted between the strands of wires *a*, as shown in Figs. 1 and 2. These two parallel flanges, together with the front of the frame *I*, thus form a frame by which the picket is guided to place 85 and in which it is held during the twisting. The standard *C* is moved so as to tighten the wires to the requisite degree, and the crank-shaft is turned so as to cause the twist-ers to rotate, and thereby twist the wires and securely 90 fasten the picket thereto. When the frame *I* is moved laterally a suitable distance on the wires, another picket is inserted therein, and a reverse rotary motion is imparted to the twist-ers to secure the said picket, and so on 95 for each additional picket. At suitable intervals the wires are fastened to ordinary fence-posts by means of staples.

In order to prevent the fence thus constructed from sagging, I provide a brace-wire, 100 *z*, which is secured at one end to the upper end of the corner-post, and is drawn diag-

nally across each panel to the center thereof, and interlaced upon the lower ends of the central pickets, and then drawn diagonally upward across the said panel to the next post, 5 and there secured, and so on with each additional panel.

Having thus described my invention, I claim—

- 10 1. The combination of the frame I, having the parallel flanges R on its frontside, thereby forming a guiding-frame to receive and hold the picket, and the rotating twistlers journaled in the frame I, for carrying the wires and twisting the same behind the picket, substantially 15 as described.

2. The combination of the standard C, having the slots e, the arms B, carrying the spools for the wires, the bars F in the slots e, and bearing on the upper sides of the arms, and the wedges for regulating the tension of the 20 bars and arms on the wires, for the purpose set forth, substantially as described.

In testimony that I claim the foregoing as my own I have hereto affixed my signature in presence of two witnesses.

WILLIAM H. McGREW.
